UNITED STATES PATENT OFFICE.

GUNTHER LUCKEMAN, OF MORSEMORE, NEW JERSEY.

IGNITION SYSTEM.

Application filed December 22, 1924. Serial No. 757,560.

To all whom it may concern:

Be it known that I, GUNTHER LUCKEMAN, a citizen of the United States, and a resident of Morsemere, in the county of Bergen and 5 State of New Jersey, United States of America, have invented a new and Improved Ignition System, of which the following is a full, clear, and exact description.

This invention relates to timers for the 10 well known Ford ignition system, and has for its object the provision of a device for causing the secondary current to produce a spark in the plugs.

A further object of the invention is the 15 provision of a device causing distribution of the secondary current from a single coil to the spark plugs of the well known Ford ignition system.

This invention will be best understood 20 from a consideration of the following detailed description, in view of the accompanying drawings forming part of the specification; nevertheless it is to be understood that the invention is not confined to the disclosure 25 sure, being susceptible of such changes and modifications which shall define any material difference from the salient features of the invention as expressed in the appended claim.

30 Fig. 1 is a front view of a timer constructed in accordance with the principles of my invention.

Fig. 2 is a vertical section taken along the line 2—2 of Fig. 1.

35 Fig. 3 is a vertical section taken at right angles to the section shown in Fig. 2 and along the line 3—3 of Fig. 2.

Fig. 4 is a view in elevation of a primary distributor.

40 Fig. 5 shows more or less diagrammatically an ignition system.

Referring more particularly to the drawings, 1 designates a coil box having primary terminals 2 and 3 for connecting the primary 45 coil with the primary circuit of the distributor.

A source of current 4 is connected through terminal 2 with the primary coil and the circuit is completed through a wire 5, a carbon contact brush 6, a distributor 7, timer shaft 8 and wire 9. The distributor 7 is driven by the shaft and through which the primary circuit is grounded.

50 The rotatable member which is driven by the shaft 8 comprises an insulated block 10 in which the distributor 7 is mounted and

locked upon the reduced portion of the shaft by a nut 11. The insulated member 10 has a projection 12 carrying a brush 13 slidably mounted in a pocket 14 of the projection 12 and is maintained in an operative position by means of a spring engaging a brush 15 screwed into a threaded perforation at the inner end of socket 14. The spring presses in opposite directions for forcing the brush 13 in an outwardly projected position. The casing 16 formed of insulating material is circular in formation and upon its inner periphery is provided a plurality of spaced contacts 17, 18, 19 and 20. These contacts 70 as shown in Fig. 5 are electrically connected by suitable wires with their respective spark plugs generally designated by the numeral 21. The contacts 17 to 20 inclusive are adapted to be engaged by the brush 13 which is electrically connected by means of a spring 22 with the brush 15 which is adapted to be in constant contact with a collector ring 23. The collector ring 23 is electrically connected by a wire 24 passing through the insulated casing 16 with the terminal 25 of the secondary coil. The wires leading from the contacts 17 to 20 inclusive to the spark plugs 21 and the wires leading from the collector ring to the secondary binding post 25 are 80 all mounted in a plate 26 secured at the front face of an enlargement 27 at the upper end of the casing 16 which forms an extension of the insulating material of said casing, the terminals of said wires being embedded in said material.

The casing 16 is closed by a cover 28 adapted to be removably held in position on the casing in the usual manner and is provided with an insulated plug 29 carrying the 90 carbon contact brush 6. The wires generally designated by the numeral 30 form a connection between the spark plugs 21 and the contacts 17 to 20 inclusive.

The operation of my device is as follows: 100

The primary circuit of the battery 4 is completed as described through the primary coil of the box 1 and is periodically closed through the brush 6 engaging the contacts 31, 32, 33 and 34 consecutively and at the time the brush 13 makes contact with the respective stationary contacts 17 to 20 inclusive. As the primary current is periodically closed the secondary current will 105 periodically flow through the collector ring 23, the brushes 15 and 13 and through the contacts 17 to 20 consecutively and cause 110

sparks in the respective spark plugs 21. In this manner the secondary current is the medium for producing a spark in said plugs.

- A cap screw 29^a is threaded into the plug 5 and maintains a spring 35 under tension for forcing the brush 6 into engagement with the contacts 31 to 34 inclusive. The spring and screw electrically connect brush 6 and wire 5.
- 10 The plate 26 which is secured to the casing is provided with an opening 36 adapted to receive the bent end of a link which is connected with the spark lever mounted adjacent the seat of the driver. When the spark 15 lever is operated the plate is oscillated to cause rotation of the casing and thereby advance or retard the spark, or, in other words the several brushes are angularly displaced relative to the cam shaft 8.
- 20 It will be noted that the outer projecting end of the screw or brush 15 is slightly

spaced from the ring which will provide a jump gap for the secondary current when the secondary circuit is closed.

I claim:

25 A timer-distributor unit for an ignition system having a primary and secondary circuit and spark plugs, comprising in combination a rotatable member having spaced contacts, a brush adapted to periodically connect the spaced contacts with the primary circuit, a conductor ring electrically connected with the secondary circuit, stationary contacts adapted to be electrically connected with the spark plugs, a pair of 30 brushes periodically connecting the ring with the stationary contacts, a casing formed of insulating material and carrying the stationary contacts, and a cover for the casing, 35 said first mentioned brush being slidably 40 mounted in the cover.

GUNTHER LUCKEMAN
